UNITED STATES PATENT OFFICE

171,017

TABLE

Franz Wagner, Evanston, Ill., assignor to Arvin Industries, Inc., Columbus, Ind., a corporation of Indiana

Application September 27, 1952, Serial No. 21,613

Term of patent 14 years

(Cl. D33—14)

To all whom it may concern:

Be it known that I, Franz Wagner, a citizen of the United States, residing at Evanston, Illinois, have invented a new, original, and ornamental Design for a Table, of which the following is a specification, reference being had to the accompanying drawing forming a part hereof.

The single figure is a perspective view of a table showing my new design.

I claim:

The ornamental design for a table, as shown.

FRANZ WAGNER.
